McLaughlin & Hill

Dressing Leather

X 9628

Patented Apr 28, 1836.

Ira McLaughlin & Horace Hill
Letters Patent

The schedule referred to in these Letters Patent and making
of the same containing a description in the words of the said Ira
McLaughlin & Horace Hill themselves of their improve-
ment in the Machine for Swelling Leather.

To all persons to whom these presents shall come. Be it
known that we Ira McLaughlin & Horace Hill both of
Sandgate, County of Bennington and state of Vermont
have jointly, invented a new and useful improvement in
the common pendulum rolling machine, used for rolling
leather which improvement or invention we specify and
describe in manner following viz To show the nature prop-
erties and extent of our improvement we here describe a ma-
chine for a size suitable for rolling leather. The drawing exhibit
its a perspective view of the machine here described and refe-
rences are made to the same in the description. In the construc-
tion of the machine some kind of hard wood should be used.
The table or platform (a) is sixteen feet long four feet wide and
four inches thick raised three feet from the floor and resting
on four supports. To this table is firmly framed two upright
or perpendicular posts (b, b) eight feet in length, four inches
wide and eight inches thick resting one foot from the front
and six inches from the ends of the table. To each side of these posts
and two feet six inches distance from the table or base are fit-
ted or framed two cross pieces or girts (c) fifteen feet long six inches
wide and two inches thick. Also to the posts six feet and six
inches from the table is framed a beam (d) sixteen feet long and
one foot square. To the post standing on the right end of the table and
three inches below the top of the same is attached by a movable
joint a weight beam (e) nine feet long one foot wide and
one inch thick in this beam is placed the weight necessary for the op-
eration

action of rolling the leather. To the weight beam, and eight feet from the moveable joint by which it is attached to the posts is connected by a moveable joint a pendulum (f) passing through a wide mortice in the main beam and between the two girts, eight feet long, four inches thick and one foot wide at the lower end. To the lower or wide ^{end} of the pendulum is fitted a brass roller (g) six inches long and four inches diameter with an iron guard one foot long passing through the centre of the roller. Directly under the end of the weight beam, is framed or fitted into the upper side of the main beam a block (h) or rest of sufficient height for the weight beam to rest upon after the pendulum has swung fifteen inches past the centre of motion. To the pendulum and one foot and six inches above the roller is connected by a moveable joint a sweep (i), passing through a wide mortice in the right post the end of which is to be attached to a crank, to which the power is applied that moves the machine. What we claim as our invention or improvement is that part of the construction of the machine, which raises the roller from the leather after it has passed a certain distance either very fast the centre of motion, by means of which the leather can be moved and placed under the roller, without the trouble or inconvenience of moving or displacing the weights or power as in the common way. But we do not claim as any part of our invention the whole or any of the parts of the above described machine formerly in use or the particular size or shape of the same any further than is necessary to effect the self-raising of the roller from the leather during the operation of rolling.
